JAMES MUNDORFF, OF SHARON, PENNSYLVANIA.

WATER-HEATING SYSTEM.

1,113,238.

Specification of Letters Patent. Patented Oct. 13, 1914.

Application filed May 16, 1913. Serial No. 768,027.

To all whom it may concern:

Be it known that I, JAMES MUNDORFF, a citizen of the United States, residing at Sharon, in the county of Mercer and State 5 of Pennsylvania, have invented certain new and useful Improvements in Water-Heating Systems, of which the following is a specification.

My invention relates to improvements in 10 pressure regulators for hot water heating systems.

In hot water heating systems, it is necessary to maintain all of the circulation pipes completely filled with water. During the 15 operation of the system unavoidable leakage and evaporation will occur, particularly in the valves and at points where the pipe fittings connect. For that reason, it is essential to provide a constant supply of 20 water which may be automatically passed into the system to replace that which has left it. In accomplishing the latter, however, it is necessary to prevent the passage of the hot water from the system back into 25 the reservoir, in that, satisfactory water temperature can only be maintained under pressure.

In the present invention, my purpose is 30 the construction of such a system as will permit of all the usual functions of a hot water circulating system and at the same time, permit of the water being maintained at a much higher pressure, and consequently, at a much higher temperature than 35 has heretofore been obtained. This result has been obtained by the employment of structure and arrangement of parts such as that shown in the accompanying drawing.

In the drawing, Figure 1 is a side elevation 40 of a portion of a hot water circulating system, showing the connection between the water reservoir and the system supply, a portion of the structure therein shown being broken away to permit of its being 45 more readily understood. Fig. 2 is a side elevation of the water reservoir with the condenser and waste pipe connected thereto.

Referring now to these drawings, A is a 50 cylindrical chamber; B a chamber of similar design, but substantially larger in capacity. Connecting the bottom of these two chambers is an inverted goose neck tube C, the ends of which are open and extend up into the chambers A and B respectively.

55 At the bottom of each chamber, the tube

is provided with a number of small holes, E and E'. Positioned near the top of each chamber and extending over the ends of the tube are the baffles F—F'. Connecting the upper portion of these two chambers are 60 the pipes and fittings G—G', interpositioned in which is the check valve H so set as to prevent a passage of water from the small into the large chamber. Small openings provided with suitable closures 65 K—K' are provided at the bottom of each of the two chambers, whereby access is afforded to each of these two chambers for the purpose of cleaning, etc.

The pipe A' connects the smaller chamber with the hot water circulating system. Extending upwardly from the top of the chamber B, is a fitting L having a conical open top member L' connected to the top thereof. L' is shown in outline positioned 70 within the collar M, at the lower part of which collar is an outlet provided with a suitable closure M'. Connected to the top of the collar M is the pipe N', which is connected to the T N. Extending horizontally 75 from T N is the pipe O, hand valve P and the pipe R leading to the initial water supply. Extending upward from the T N is the pipe S leading to the water reservoir T, this water reservoir having the water gage 80 85 W thereon. Extending from the top of the reservoir is the pipe U leading into the expansion chamber V. Connecting to the top of this chamber is a T from the upper portion of which extends the air vent X and 90 from the side of which extends the waste pipe Y.

When my device is in operation the tube C is supplied with a mercury column D which normally rests with its upper ends 95 at the points D'.

Explaining now the operation of the foregoing structure, it may be well to take it, first under normal conditions, then where there has been deficiency of the water contents created and lastly when the water pressure has become abnormally high.

There being unfilled water space in the circulation pipes, water flows from the reservoir T through the members S, N, N', M, L', 105 L, G' and H, where the valve swinging to the right permits it to pass into the pipes G, top of the chamber A and on through A' into the circulation pipes. In its passage into the member M dirt and sediment will be col- 110

lected by the trap L' and at suitable intervals can be removed therefrom by removal of the closure M'. It must of course be understood, that this apparatus, in common with all others now in the market, is positioned in the attic where the water will normally flow into the system by gravity. The pipe now being filled and the pressure having risen to an abnormal degree, the water 10 in expanding is prevented from passing directly into the chamber B on account of the check valve H. All of the pressure is therefore exerted against that end of the mercury column below the chamber A, and as the 15 pressure increases that end of the column is depressed and the end leading into chamber B correspondingly raised. When eventually the pressure becomes too strong, the mercury is forced out through the top of the 20 tube C into the chamber B, where it may under great pressure strike the baffle F' and be thrown down against the bottom of the chamber. The mercury will then drain slowly through the holes E' back into the 25 hole C. The purpose of preventing its rapid passage back into this tube is to eliminate any air pockets therefrom. Under a sudden reduction of pressure, should the mercury pass rapidly back into the chamber A, the 30 action of the mercury will be exactly similar as to that in chamber B.

When the gage shows that the water is low 35 in the reservoir T, the hand valve P is opened to admit of fresh water direct. If, under extreme rise in the pressure, the hot water is forced up into the reservoir T, any steam condensed in the chamber V is returned to the system, while any undue overflow is taken care of by the overflow pipe Y 40 which leads into the sewer or some suitable drainage.

From the foregoing description, it must be realized that I have provided means for supplying the system with water which is 45 not interfered with by any mercury column or well, and when there is sufficient water, while at all times preserving safety, the full resistance of a mercury column is opposed to the heated water. By the employment of my 50 system, I have been enabled to use pipes of as small diameter as $\frac{3}{8}$ ", and maintain a temperature as high as 258°.

I claim,

1. In a water heating system, the combination of two chambers, a U-shaped pipe connecting the bottoms of said chambers and having a mercury column therein, and a second pipe leading from the top of one chamber to the top of the other and having

therein means for preventing the passage of 60 water therethrough in one direction only.

2. In a water heating system, the combination of two chambers, a pipe having its ends entering and extending above the bottoms of 65 said chambers, perforations in each end adjacent said bottoms, a second pipe, having a check valve therein, connecting said chambers and means in said first pipe opposing the flow of water therethrough, as, and for 70 the purpose, set forth.

3. In a water heating system, the combination of two chambers, a baffle plate in each chamber, a pipe, having a check valve therein, entering said chambers above the baffle and a second pipe, located exteriorly of the 75 chamber and having a mercury column therein, entering, and extending above the bottom of said chambers, said second pipe having its ends perforated above and adjacent the bottoms of the chambers. 80

4. In a water heating system the combination of two chambers, baffles located at the upper end of each chamber, a pipe having a check valve therein connecting the tops of 85 said chambers, a U shaped pipe entering and extending above the bottom of said chambers and terminating below the baffles, perforations in both ends of the latter pipe, said perforations being flush with the bottom of the interior of the chambers, and a 90 mercury column within said latter pipe, as and for the purposes set forth.

5. In a water heating system, the combination of two chambers, baffles therein, two pipes exteriorly located connecting said 95 chambers, one of said pipes containing a mercury column which is normally free from both chambers, and the other a check valve, one of said chambers connecting directly with the main system and an expansion 100 tank connecting with the other chamber.

6. In a water heating system the combination of two chambers, two pipes connecting the same, one of said pipes containing a mercury column, which is normally below 105 the bottom of both chambers, and the other a check valve, a source of water supply, a trap between the latter and one of said chambers, an expansion tank, a reservoir connected thereto, and pipes connecting said 110 reservoir and trap.

In testimony whereof I affix my signature in presence of two witnesses.

JAMES MUNDORFF.
